US00D839508S

(12) **United States Design Patent** (10) Patent No.: **US D839,508 S**
Chung et al. (45) Date of Patent: ** Jan. 29, 2019

(54) **WATER REMOVAL APPARATUS**

(71) Applicant: **LG ELECTRONICS INC.**, Seoul (KR)

(72) Inventors: **Wookjun Chung**, Seoul (KR); **Younghoo Ha**, Seoul (KR); **Eunyoung Chee**, Seoul (KR); **Jaeil Bae**, Seoul (KR); **Yoonji Lee**, Seoul (KR)

(73) Assignee: **LG ELECTRONICS INC.**, Seoul (KR)

(**) Term: **15 Years**

(21) Appl. No.: **35/504,057**

(22) Filed: **May 26, 2017**

(80) **Hague Agreement Data**

Int. Filing Date: **May 26, 2017**

Int. Reg. No.: **DM/098064**

Int. Reg. Date: **May 26, 2017**

Int. Reg. Pub. Date: **Dec. 1, 2017**

(30) **Foreign Application Priority Data**

Nov. 28, 2016 (KR) 30-2016-0057178

(57) **CLAIM**

The ornamental design for a water removal apparatus, as shown and described.

DESCRIPTION

1. Water removal apparatus

1.1 : Perspective

1.2 : Front

1.3 : Back

1.4 : Left

1.5 : Top

1.6 : Bottom

1.7 : Back perspective view

1.8 : Exploded

The broken lines depict portions of the water removal apparatus that form no part of the claimed design; reproduction 1.1 is a front perspective view of the water removal apparatus; reproduction 1.2 is a front view thereof; reproduction 1.3 is a back view thereof; reproduction 1.4 is a left view thereof where the right view is a mirror image;

(Continued)

reproduction **1.5** is a top view thereof; reproduction **1.6** is a bottom view thereof; reproduction **1.7** is a back perspective view thereof; reproduction **1.8** is a front perspective view thereof showing a disassembled state in which the head part is detached.

1 Claim, 8 Drawing Sheets
